UNITED STATES PATENT OFFICE.

ALFRED A. GRUNDY, OF PHILADELPHIA, PENNSYLVANIA, ASSIGNOR OF ONE-THIRD TO HIMSELF, ONE-THIRD TO GEORGE GRUSHLAW, AND ONE-THIRD TO JOHN SICHEL, ALL OF PHILADELPHIA, PENNSYLVANIA.

MACHINE FOR MAKING KNITTED PILE FABRICS.

Application filed September 18, 1924. Serial No. 738,332.

To all whom it may concern:

Be it known that I, ALFRED A. GRUNDY, a citizen of the United States, residing at Philadelphia, county of Philadelphia, and 5 State of Pennsylvania, have invented a new and useful Improvement in Machines for Making Knitted Pile Fabrics, of which the following is a full, clear, and exact description, reference being had to the accompanying drawings, which form a part of this 10 specification.

The object of my invention is to produce a knit pile fabric.

The usual method of producing such a 15 fabric involves knitting, on one machine, a fabric containing elongated loops, and on another machine cutting such loops to form the pile. These operations, because they require the use of two machines, involve delay 20 and expense; and, moreover, the cutting knives speedily lose their cutting edges and must be frequently replaced.

The machine embodying the present invention is adapted to the manufacture of 25 pile fabric on one machine. This machine is preferably a circular machine of the rib knitting type, differing from a machine of ordinary construction in respect to the special means employed for producing the 30 special pile-forming loops, and in respect to the peculiar means provided for cutting the loops, which means not only operate during the knitting operation but are of such a character that they are virtually immune 35 against wear.

The knitting mechanism comprises a bank of needles extending and reciprocating in one direction (say vertically) and operating simultaneously on two threads; a bank 40 of "dummy needles", or bars, extending and reciprocating in another direction (say horizontally or radially) and adapted to engage one thread; and two yarn feeds, one on one side (say above) the plane of the radial bars 45 and the other on the other side (say below) the plane of the radial bars. If the needles be assumed to be the vertical needles of a rib knitting machine and if the radial bars be assumed to be substituted for the dial or 50 radial needles of a rib knitting machine, and if these needles and bars be operated the regular way, one thread will be looped over the bars and the other under the bars, forming thus normal interconnected loops that

do not engage the bars and long floating 55 loops that are looped over the bars. The tension devices which pull down the fabric as it is knit act to elongate the bar-engaging or floating loops to the desired length.

The cutting mechanism comprises essentially 60 a bite roller which rolls over and presses down on the yoke portions of the loops while they are stretched over the bars, thereby severing them and forming the up-standing pile. It is found that this roller 65 action is perfectly and reliably effective to sever all the loops, and in the absence of any cutting edge, the factor of abrasion is substantially eliminated and the rollers have a long and perhaps practically unlimited 70 life.

While I have referred to but one pair of thread carriers, it will be understood that there may be a plurality of pairs of thread carriers—say two to eight—the number 75 varying with the diameter of the machine. Where the machine is used to make piece goods and is therefore of substantial diameter, it is desirable to provide more than one pair of thread carriers. Four pairs of 80 thread carriers are practicable on the ordinary circular machine intended for the production of these goods. The mechanism, including the cams for actuating the needles and the loop-forming bars, and the loop-severing roller, is duplicated for each pair 85 of thread carriers.

The machine shown in the accompanying drawings, which shows a preferred embodiment of my invention, comprises four sets 90 of knitting and pile forming mechanism.

Fig. 1 is a plan view of the dial cam plate, its cams and the loop-cutting rollers.

Fig. 2 is an enlarged plan view of a part 95 of the machine shown in Fig. 1.

Fig. 3 is a front view of part of Fig. 2.

Fig. 4 is a radial cross-section through the cylinder, the dial and the loop-cutting mechanism.

Fig. 5 is a front view of a few of the cylinder needles and dial bars and a pair of 100 thread guides.

Fig. 6 is a diagram of the fabric.

a, a are the vertical cylinder needles of a 105 rib knitting machine and are vertically reciprocable in the usual way by cams (not shown). *b, b* are bars corresponding to the radial or dial needles of such a machine and

are similarly associated with the cylinder needles and are reciprocable radially by cams *d*, *e* and *f*, *g* and *h* (see Fig. 5) represent yarn guides located opposite cam *e*.

5 One of these guides delivers yarn *x* from above the plane of the dial bars and the other delivers yarn *y* from below the plane of the dial bars.

With needles, bars and yarn guides ar-

10 ranged as described, and operating the needles and bars in the usual way, the vertical needles *a* will engage both threads *x* and *y* simultaneously and form plain loops; but in the projection of the dial bars *b*, the 15 thread *x* delivered from above the plane of the dial bars will be laid over these bars and therefore their yoke portions will not engage the necks of the adjacent course of loops and will not unite adjacent courses of knitting.

20 The machine shown is one in which the needle-actuating cams and bar-actuating cams are stationary and the needles and bars rotate (although a reverse arrangement will be understood to be the full equivalent). As 25 the newly formed loops advance, the tension imposed on the fabric already knit tends to tighten the adjacent interlocked courses of newly formed loops of yarn *y*; but the effect upon the loops of the yarn *x* is to still 30 further elongate them preparatory to cutting them to form the pile.

As the needles and bars travel toward the point of yarn severance, the bars are extended beyond the edge of the dial *i* and the 35 loops formed by the yarn *x* are nearly in alignment with the outer edge of the dial, while the knitting fabric extends down between the periphery of the dial *i* and the inside of the needle cylinder *j*. At the point of 40 severance, the stationary overlying dial cam plate *k* is cut away to accommodate a roller *m* turnable, in roller bearings, on a shaft carried on a member *n* slidable in a frame *o* secured to the dial cam plate *k*. A coil 45 spring *p* is confined between the chamber *n* and a disc *r* adjustable by means of a screw *s*.

As the dial bars *b* rotate in the direction of the arrows, Figs. 2 and 3, the roller *m* rolls over their upper surfaces with a degree 50 of pressure that is adjustable by means of the screw *s* and spring *p*. The pressure may be made sufficiently great to bite the yarn between the roller and the underrunning 55 dial bars *b* and sever all the loops successively.

It is not necessary that the pressure applied by the roller *m* shall be a yielding one; but this is desirable in case any of the 60 dial bars are not precisely in the common plane of the other bars. Thus, if any one of the dial bars are below the level of the other bars, the spring-pressed roller will nevertheless roll over such bar with practically the same degree of force as it rolls

over the other bars and will sever the yarn looped thereover with the same degree of certainty that it severs the yarn of the other loops. A rigid roller is workable, but in case of the depression of one of the dial bars slightly below the level of the others, the roller may fail to sever the corresponding loops and leave a stripe effect in the finished fabric which may somewhat mar its appearance.

75 The considerable pressure imposed by the roller *m* on the dial bars *b* is close to the overhanging ends thereof and is likely, after long continued operation of the machine, to impose a severe strain on them. To afford a support for the overhanging end of the dial bars, I secure to the fixed part of the machine, directly underneath the roller *m*, a bracket *u* (see Fig. 4) on which is 80 mounted a roller *v*, whose periphery extends underneath the outer ends of the dial bars *b* and affords a supporting surface over which each bar rolls as it is being subjected to the downward pressure of the bite roller *m*.

85 In Fig. 6 is shown a diagram of a small section of fabric including several wales and several courses. The last knit course of loops formed by the yarn *x* is shown pulled taut over dial bars *b* before they are cut by the bite roller *m*. The previously knit courses of loops formed by the yarn *x* are 90 shown as cut to form a pile effect on the fabric; the body of the fabric being composed of normal loops formed by the yarn *y*.

95 Having now fully described my invention, what I claim and desire to protect by Letters Patent is:

1. In a knitting machine, the combination with traveling needles and yarn-holding bars adapted to cooperate to form elongated loops engaging the bars, of a bite-roller stationary relative to the bars and positioned, in the travel of the latter, to roll over the bars and press the yarn between it and the 100 bars and thus effect the severance of the yarn.

2. In a knitting machine, the combination with mechanism adapted to form courses of loops of one yarn and courses of loops of another yarn extending through loops of the other course and elongated to form a plush-like surface, said mechanism including bars over which said elongated loops extend, and a bite roller adapted to roll over 110 said bars and bite and sever the yarn of said loops.

115 3. In a knitting machine, the combination with mechanism adapted to form a series of loops of one yarn interengaging to form a plain knitted web and a series of loops of another yarn extending through the loops of the first series and elongated to form a plush-like surface, said mechanism including bars over which said elongated loops ex-

- tend, and a member presenting a rolling surface adapted to roll over said bars and bite and sever the yarn of said loops.
4. In a knitting machine, the combination with a series of vertically extending reciprocal traveling needles, of a series of horizontal extending traveling bars, a yarn feed adapted to deliver yarn under the bars to said needles whereby the latter knit plain web loops, a yarn feed adapted to deliver yarn over said bars to said needles to form pile-forming loops, and a roller stationary relative to the bars and positioned, in the travel of the latter, to roll over the bars and 10 press the yarn of the loops between it and the bars and thereby sever the yarn.
5. In a knitting machine, the combination with a series of vertically extending and reciprocal traveling needles, of a series of radially extending and reciprocal traveling bars, and yarn feeds one of which is adapted to deliver yarn direct to needles and the other of which is adapted to deliver 20 yarn over said bars to needles, said bars adapted to elongate the loops formed thereon and hold the yoke portions of the loops of a course from engaging the necks of an adjacent course of loops, and a bite roller adapted to roll over said bars and bite and 25 sever the yarn of the elongated loops.
6. In a knitting machine, the combination of a yarn feed and a series of reciprocal needles adapted to engage yarn from said feed and knit it into a plain web, a second yarn feed adapted to deliver yarn to said needles, a series of bars adapted to engage 30
- yarn fed from the second feed and elongate the loops formed thereby, said needles operating to draw both yarns through loops formed by the first yarn but being restrained by said bars from drawing yarn through 35 loops formed by the second yarn, and a bite-roller adapted to roll over the yarn looped over said bars and by its pressing action sever the yarn and form a pile.
7. In a knitting machine, the combination with knitting mechanism and yarn-holding bars adapted to cooperate to form elongated loops engaging the bars, of a bite-roller adapted to roll over the bars and the yarn looped thereon, and a spring adapted to impose a strong but yielding pressure on the roller and thereby insure its operation notwithstanding a variation in the level of the loop-holding bars.
8. In a knitting machine, the combination with travelling needles and yarn-holding bars adapted to cooperate to form elongated loops engaging the bars, of two rollers stationary relative to the bars, one roller adapted to roll over the bars and press the yarn 50 of the loops between it and the bars to sever the yarn, and the other roller adapted to roll under the free ends of the bars and afford a support therefor while the other roller is 55 pressing down upon the bars.
- In testimony of which invention, I have hereunto set my hand, at Philadelphia, Pennsylvania, on this 17th day of September, 1924.

ALFRED A. GRUNDY.
